(57) **CLAIM**

The ornamental design for a plumbing fitting, as shown and
described.

DESCRIPTION

In a preferred embodiment, the nature of this product is a
plumbing fitting, or portion thereof, in the form of a support
bar for supporting items such as towels or a handle for
grasping when entering shower enclosure.

FIG. 1 is a left, top, front perspective view embodying my
new design;

FIG. 2 is a front elevational view thereof;

FIG. 3 is a left side elevational view thereof, the right side
elevational view thereof being a mirror image of the left side
shown; and,

FIG. 4 is a top plan view thereof, the bottom plan view being
a mirror image of the top view shown.

The broken line representations of mounting structure in the
figures are for the purpose of illustration only, and form no
part of the claimed design.
